CLAIM

The ornamental design for a food container assembly, as shown and described.

DESCRIPTION

For purposes of understanding the context and usage of the food container assembly, each of the following U.S. patent applications and their corresponding U.S. patent application publications are incorporated herein by reference: U.S. patent application Ser. No. 12/028,824; U.S. patent application Ser. No. 12/028,825; U.S. patent application Ser. No. 12/028,826; U.S. patent application Ser. No. 12/028,827; U.S. patent application Ser. No. 12/028,828; and U.S. patent application Ser. No. 12/028,829.

FIG. 1 is a top and front perspective view of a food container assembly showing our new design;

FIG. 2 is a top plan view thereof; and,

FIG. 3 is a side elevation thereof, the other sides being identical.
